UNITED STATES PATENT OFFICE.

ALLEN S. WISE, OF PITTSBURGH, PENNSYLVANIA, ASSIGNOR TO WESTINGHOUSE ELECTRIC & MANUFACTURING COMPANY, A CORPORATION OF PENNSYLVANIA.

IRONING MACHINE.

application filed May 22, 1924. Serial No. 715,106.

My invention relates to laundering machine, including wringers, mangles and ironing machines and has special relation to ironing machines.

5 The primary object of my invention is to provide a motor drive for a roll in a device of the class described, in which the reaction to the force required for rotating the roll is utilized to press a laundering member 10 which cooperates with the roll against the roll.

Another object of my invention is to provide a laundering machine in which the pressure of a laundering member against a 15 roll, with which the laundering member cooperates for laundering, is operative by reaction after the initial operation of the laundering member.

20 A still further object of my invention is to provide a laundering machine in which the exertion of a small amount of force by an operator is augmented by power mechanism to produce great pressure between two laundering members which cooperate for laundering purposes.

25 A still further object of my invention is to provide a simple and inexpensive power mechanism for moving a laundering member into operative relation with a second laundering member for direct laundering action on articles to be laundered.

Reference is had to the drawings in which: 30 Figure 1 is a transverse sectional view through an ironing machine constituting an embodiment of my invention, a roll and shoe being shown in broken lines in the ironing or contacting positions thereof.

35 Fig. 2 is a view, similar to Fig. 1, showing the shoe and roll in broken lines in the separated positions thereof.

Fig. 3 is a plan view of the machine, and

40 Fig. 4 is a rear elevational view of the machine.

Although the invention is capable of embodiment in various types of laundering machines, including mangles and ironing machines, it is illustrated and described as embodied in an ironing machine comprising a roll 1, a shoe 2 and a motor 3.

The roll 1 is mounted for rotation on a pair of standards 4 and 5 and, for that purpose, is provided, at one end, with a spider 6 which receives a shaft 7, journaled in the standard 4.

55 A sprocket wheel 8 is rigid with an end of the shaft 7 and the other end is provided with a pin 9 adapted to cooperate with a pair of plungers 10 slidable through apertures in the spider 6 and rigid with a clutch collar 11. The clutch collar 11 receives the 60 end of an arm 13 of a bell crank pivoted on the standard 4. A control handle 14 is pivoted on the other arm 15 of the bell crank and is apertured to receive the bent end of a link 16 which extends through an opening 65 in a lever 17 which supports the trunnion 18 of the shoe 2. The other end of the shoe 2 is pivoted on a lever 19 similar to the lever 17. The levers 17 and 19 are rigid with a rock shaft 24 journaled in standards 4 and 5.

70 On one side of the lever 17, a shoe-compression spring 20 is provided which surrounds the link 16 and is retained in position by a nut 21. On the other side of the lever 17, a shoe-release spring 22 is provided which surrounds the link 16 and engages, at one end, a collar 23 on the link 16.

75 An additional lever 25 is secured to the rock shaft 24 and carries, at its upper end, 80 a pin 26 on which a sprocket wheel 27 is mounted for rotation and from which depends an arm 28 rigid with the casing 30 of a reduction mechanism (not shown). The reduction mechanism is driven by the 85 motor 3 and transmits power to a sprocket wheel 31 mounted on the casing. A chain 32 passes over the sprocket wheels 31, 27 and 8.

90 In the operation of the device, when it is desired to move the shoe 2 from the position shown in dotted lines in Fig. 2, the motor is started by means of a switch (not shown) and the control handle 14 is swung forwardly from the position shown in Fig. 2 to the 95 position shown in Figs. 1, 3 and 4. Movement of the control handle 14 operates to move the lever 17 and shoe 2 and establishes a light pressure contact between the shoe 2 and the roll 1.

100 The movement of the control handle 14 also operates to move the arm 15 of the bell crank rearwardly and to thus throw the clutch collar 11 inwardly, the plungers 10 being projected adjacent to the pin 9.

105 The rotation of the sprocket wheel 31 moves the endless chain 32 and the sprocket wheels 27 and 8.

Slight turning of the sprocket wheel 8 brings the plungers into engagement with the pin 9. The load of the roll is then imposed upon the endless chain 32, the tensioning of which results in a tendency for sprocket wheel 27 to move toward sprocket wheel 8. This tendency to movement exerts a force upon the lever 25, the shaft 24 and the levers 17 and 19. After the building up 10 of pressure between the shoe 2 and the roll 1 to a point corresponding to normal operating conditions, the chain 32 operates to rotate the roll 1.

The spring 20 exerts force on lever 17 15 which is transmitted to the shoe 2 and produces shoe pressure on the roll 1. This pressure tends to oppose rotation of the roll 1 and, therefore, requires greater tension in the endless chain 32 to produce rotation in 20 the roll 1. The increase in the tensioning of the chain 32 operates to exert greater force on sprocket wheel 27, tending to urge the sprocket wheel 27, the lever 25, the levers 17 and 19 and the shoe 2 toward the roll 1. 25 It is apparent, therefore, that, when the operator moves control handle 14 and compresses spring 20 manually, the force which he exercises is greatly augmented by the motor 3, and great pressure is produced by 30 the shoe 2 on the roll 1. In this operation, a principle of reaction is utilized. The reaction to the force required to rotate the roll 1 is directed to producing pressure by the shoe 2 on the roll 1. This ensures sufficient 35 pressure for good ironing.

When it is desired to move the shoe 2 away from the roll 1, the control handle 14 is moved by the operator from the position shown in Figs. 1 and 3 to the position 40 shown in Fig. 2. The movement of the handle 14 releases the pressure of the spring 20 on the lever 17 which reduces to a certain extent the pressure of the shoe upon the roll, whereby the force required to operate the 45 roll is appreciably reduced and the levers 25, 17 and 19 tend to move to the left of the position shown in Fig. 1. The tendency of the levers to move to the left further reduces the pressure of the shoe upon the roll, and 50 since this tendency is cumulative, the levers finally assume the position shown in Fig. 2. The levers are normally biased to this position by the weight of the motor and gearing suspended from lever 25, so that upon the 55 decrease in tension of the chain 32, a movement of the levers to the left results. The handle 14 may be urged further rearwardly to compress the spring 22 on link 16, thereby urging lever 17 and shoe 2 away from the 60 roll, in the event that the material being laundered is of such a character that the shoe tends to stick in engagement with the roll. Normally, however, the weight of the motor and gearing is sufficient to move the levers 17 and 19 to the left to effect the dis-

engagement of the shoe and roll. After the shoe 2 has been moved away, the arm 15 of the bell crank is free to move forwardly since the link 16 has passed beyond the point of pivotal connection of the control 70 handle 16 with the arm 15 of the bell crank. The continued urging rearwardly of the control handle 14 operates to shift the bell crank and throw the clutch out, the plungers 10 being retracted from engagement 75 with the pin 9.

The roll is then free to rotate either forwardly or rearwardly. This facilitates the arrangement of garments for ironing and, in cases where articles have become wound 80 about the roll 1, it permits the reversing of the roll for removal of the articles.

Since the greater portion of articles ironed are thin, the differences of thickness are unimportant and do not interfere with the operation of an ironing machine in the manner 85 described.

It will be apparent that the principles of the invention are of general application and may be used for establishing pressure between the cooperating elements in mangles, ironing machines and laundering appliances 90 in general.

Any drive functioning by reaction after the manner of chain 32 or any mechanism which, in its functioning to drive the roll, sets up a pressure or forceful reaction, may be used. The clutch shown and described, while a useful accessory to satisfactory manipulation of the machine as an ironer, is 95 not functionally essential to utilization of the principle of utilizing the reactive force set up.

The invention is not limited to details of construction, but the embodiment shown and 100 described may be extensively modified and varied without departing from the spirit of the invention and the scope of the appended claims. A substantial range of 105 equivalents is contemplated.

I claim as my invention:

1. In an ironing machine, the combination of a shoe, a rotary roll, means for manually moving the shoe to and from the roll, a motor for operating the roll, and means 115 operable by said motor for pressing said shoe against said roll, said means being operative by a reaction to the operating force which rotates said roll.

2. In a laundering machine, the combination of a laundering member, a second laundering member adapted to cooperate with the first-mentioned laundering member for direct action upon articles to be laundered, means for effecting the application of force by an operator for pressing said first mentioned laundering member against said second laundering member and means operative by the contact of said first-mentioned laundering member with said second laun- 120 125

dering member for automatically building up an ironing pressure between the laundering members.

3. In a laundering machine, the combination of a laundering member, a second laundering member adapted to cooperate with the first mentioned laundering member for direct action upon articles to be laundered, a control member, a resilient connection between said control member and said first mentioned laundering member for moving said first mentioned laundering member into contact with said second laundering member and means for moving said second laundering member after contact is established, said means being operative through reaction to its driving force to press said first mentioned member against the second laundering member.
- 10 4. In a laundering machine, the combination of a roll, a driven sprocket wheel for rotating said roll, a second laundering member adapted to cooperate with said roll for ironing, a second sprocket wheel supported for rotary movement with respect to said second laundering member and adapted to move therewith and a motor-driven chain ex-

tending over said sprocket wheels for rotating said roll and for pressing said second laundering member against said roll, when 30 an initial braking force is applied to the roll, thereby increasing the tension in the chain and moving the second sprocket wheel and the associated laundering member against the roll.

5. In a laundering machine, the combination of a roll, a laundering member adapted to cooperate with said roll for direct action upon articles to be laundered, a lever arm supporting said ironing member, a second lever arm operative therewith, a sprocket wheel on said second arm, a chain extending over said sprocket wheel, means for moving the laundering member to the roll, and drive means on said second lever arm for them moving said chain and rotating said roll therewith, said drive means being operative through the tension in said chain to maintain said ironing member against said roll.

In testimony whereof, I have hereunto subscribed my name this 6th day of May, 1924.

ALLEN S. WISE.
